FLOWER HOLDER

Albin John Spokus, Seattle, Wash.

Application September 27, 1943, Serial No. 503,932

3 Claims. (Cl. 24—6)

The present invention relates to a flower holder more particularly, to a holder adapted to support single flowers or corsages upon a person's wearing apparel.

Devices have been provided for holding flowers upon a person's clothes, but such devices ordinarily serve their intended purpose inadequately, since they do not firmly hold the flowers in the desired positioning, or they do so in a manner that is uncomfortable to the wearer with the wearer's clothes often being disarranged or so distorted as to produce an unattractive appearance. 5

A further and common defect lies in the fact that the flowers themselves are not properly or securely engaged and can become dislodged from the wearer's clothes or disarranged in an unsightly manner.

Having in mind the defects of the prior art, it is an object of my invention to provide a flower holder that, once locked, can only be disengaged when it is manually operated for that purpose.

Another object of my invention is to provide, in a flower holder of the type described, flower engaging means which firmly and securely grip the object being held in a manner to prevent dislodging, and without injury to the flowers.

A still further and more specific object of my invention is the provision, in a flower holder of the nature described, of flower gripping means which are simple to construct and to operate and which will not be affected by hard usage.

The foregoing objects and others ancillary thereto I prefer to accomplish as follows:

According to a preferred embodiment of this invention, my flower holder comprises an extension of a clasp. This extension supports flower impaling means as well as walls that form the sides of an inclosure about the flowers being held. One wall is stationary and movable relative to said wall is a second wall pivotally mounted to the clasp. Both walls carry flower impaling means that are disposed at an angle to each other, during times when flowers are being held. In certain instances, a hinged door upon either of said walls serves to complete the inclosure about the flowers being held and also to support decorative ornaments or the like. The movable wall of the holder is mounted upon the base plate of the clasp which is pivoted to the clasp proper in a manner more fully described hereafter.

The novel features that I consider characteristic of my invention are set forth with particularity in the appended claims. The invention itself, however, both as to its organization and its

method of operation, together with additional objects and advantages thereof, will best be understood from the following description of a specific embodiment when read in connection with the accompanying drawing, in which:

Figure 1 is a view in perspective of my flower holder illustrating the manner in which it supports a corsage or similar flower arrangement.

Figure 2 is a view in elevation of the flower holder.

Figure 3 is a plan view of the flower holder of Figure 1.

Figure 5 is a vertical sectional view taken on lines 4—4 of Figure 3, and

Figure 5 is a vertical sectional view taken on lines 5—5 of Figure 3.

A flower holder to overcome the defects hereinbefore enumerated must have at least two totally distinct characteristics; it must be capable of securely supporting and holding flowers upon wearing apparel; and, in use, it must be simple to operate for the firm engagement of the flowers being held. Accordingly, a preferred embodiment of my invention, referring to the drawing, is constituted by a clasp plate 10 having pivotally mounted on its rear face the pin 12 which swings on pivot pin 14 and is secured by the keeper 16. As is customary with such clasps, the pin 12 is inserted through the cloth and engaged in the keeper to retain the clasp 10 upon the cloth. As shown in Figure 4 an extension plate 18 depends from the clasp body 10 and has an angularly disposed wall 20 integral therewith. Extension 18 supports on its forward face a pair of flower impaling pins 22 which stand out substantially parallel to the wall 20.

On the back side of the clasp plate 10 is pivotally mounted, by means of the pin 24, the plate 26 which swings about the axis of the pin and in closed position lies directly under the plate 18. Angularly disposed on the plate 26 is the side wall 28 which has a cross-impaling pin or tine 30. Wall 28 has a slot 32 to permit the wall 28 to be swung from the position of Figure 2 to that of Figure 4, wherein the slot 32 permits the straddling of plate 10. It will be noted that the pin 30 is, in the closed position, right angularly disposed with respect to the impaling pins 22.

The stem of a flower or of a corsage to be secured in the holder is first impaled upon the pins 22 when cross-impaling pin 30 is disposed out of position as in Figure 4. The members 26, 28 and 30 are swung from the position of Figure 4 to that shown in Figures 2 and 3 whereupon the pin 30 pierces the stem of the flower or corsage in

the manner shown in Figure 3 and the latter is securely held in the holder as well as to any garment to which the holder is attached.

The front closure door 36 is hinged at 38, to wall 28 and biased to the closed position by the spring 40. As shown in Figures 2 and 3, an overlapping lip 42 engages the edge of the wall 20 to retain the door closed and the walls 20 and 28 in parallelism in the closed position. When it is desired to use the device and, assuming that it is at rest in the closed position as in Figure 2, the door 36 is opened by disengaging the lip 42 from the wall 20 whereupon the plate 26 and wall 28 is swung to the position of Figure 4. This spreads the two sets of impaling pins 22 and 30 apart into position to receive flowers to be impaled. The stems of the flowers are then laid parallel to the wall 20 and impaled upon the pins 22 in any desired arrangement, whereupon the wall 28 and the cross-tine or pin 30 carried thereby is swung back toward the previously impaled stems to cross impale the same. The door 36 is reengaged as previously. The device may then be secured by means of pin 12 upon the wearer's garment as appears attractive to that person, either in the position shown in Figure 1 or in the inverted position. In either instance the device operates equally well.

Although I have shown and described certain specific embodiments of my invention, I am fully aware that many modifications thereof are possible.

I claim:

1. A flower holder, comprising: a base plate having means for attachment of the same to a

garment; a flower stem impaling tine and a wall outstanding on said base; a plate pivotally attached to move scissors fashion with respect to said base plate and to lie in face to face relation therewith; said second plate having a flange parallel to said wall when the plates are in the closed position in which position said wall and said flange form a channel; a cross-impaling tine on said flange to intersect the stem of a flower impaled upon said first mentioned impaling tine; and means between said wall and said flange to close the channel therefrom and to latch said tines in cross-impaling position.

2. A flower holder, comprising: a base having means for attachment of the same to a garment; flower stem impaling means outstanding on said base; a wall on said base lying alongside said impaling means; a plate pivoted to said base in scissors fashion and having a flange outstanding thereon; and cross-impaling means on said flange disposed to intersect a flower stem impaled upon said first mentioned impaling means; said wall and said flange forming, in the closed position, a channel in which lies the stem of an impaled flower.

3. A flower holder, comprising: flower stem impaling means and a base for supporting the same; cross-impaling means disposed in right angular relation to said first mentioned impaling means during such times as a flower is being held; means movable with respect to said base for supporting said cross-impaling means; and a wall on said base toward which said cross-impaling means moves in approaching the closed position.

ALBIN JOHN SPOKUS.
